UNITED STATES PATENT OFFICE.

CHARLEY BURNETT, OF WASHINGTON COURT HOUSE, OHIO.

ROOF CONSTRUCTION.

1,405,966.

Specification of Letters Patent. Patented Feb. 7, 1922.

Application filed February 12, 1917. Serial No. 148,033.

To all whom it may concern:

Be it known that I, CHARLEY BURNETT, a citizen of the United States, residing at Washington Court House, in the county of 5 Fayette and State of Ohio, have invented certain new and useful Improvements in Roof Construction, of which the following is a specification.

This invention relates to roof construction and aims particularly to provide the type of structure which may be both very readily applied and which will be proof against rattling or ready dislodgment by the action of the wind when the latter 15 reaches considerable velocity.

Still a further object of the invention resides in so forming and arranging the structure that the metal roof sections, when used in connection with inclined rafters and a 20 ridge pole, may be suitably slid and overlapped and secured to the ridge pole and in this manner eliminate the possibility of wind and air from entering the interior of the structure.

25 Another object of the invention resides in a structure whereby the overlapping edges of the roof sections are secured in position to prevent the admittance of moisture to a position beneath the metal sections and to 30 also prevent corrosion of the attaching nails.

The preferred embodiment of this invention is shown in the accompanying sheet of drawings, in which similar characters of reference designate corresponding parts, and 35 in which:

Figure 1 is a partial side elevation and partial section of a roof section constructed in accordance with my invention,

40 Figure 2 is a transverse vertical section of the structure shown in Figure 1 taken on line 2-2 of Figure 1.

Figure 3 is an enlarged vertical section taken through one of the rafters, showing the manner of connecting the roof sections 45 thereto, and,

Figure 4 is a developed view of one end of the roof sections showing the bend lines as dotted lines.

In the drawings, the ridge pole is designated 50 by the reference numeral 1 and from this ridge pole there are supported a plurality of inclined rafters 2, whose top sides are preferably shaped to present a double incline, as shown at 3. These rafters are suitably spaced and are designed to support the various sheet metal roof sections 4. These

sections are preferably concaved, as is shown, and have their longitudinal edges bent to conform in shape to the rafters themselves. Along the edges of these sections, there are provided a plurality of apertures or punchings so formed that a burr 5 is formed which projects upwardly, as is shown particularly in Fig. 3. Through these apertures the attaching nails 6 are made to pass, but in order to form a tight joint and to prevent the admission of moisture beneath the roof surface each nail is provided with a washer 7, which washer is preferably of lead. As the nail is driven down, this 65 washer embeds itself in the burr formed and in turn wedges it tightly against the nail or the washer itself is embedded in this burr so that a very tight joint is formed.

70 In order to form a tight joint along the ridge pole, the end which abuts this ridge pole is slotted, as shown at 8, the depth of this slit being the amount it is necessary to bend up the flaps 9 thus formed due to the concavity of the metal plate sections. 75 Thus, by comparing Figures 1 and 2, it will be noted that the plate sections are slotted a distance sufficiently to cause a tight joint to be formed between each of the flaps 9 thus formed, the line of contact varying in 80 length from the edges toward the center. In thus bending the flaps up, the slotted ends also overlap and it is through this overlapped portion that the sections may be attached to the ridge pole, as is shown at 10. 85 This prevents the flap sections from pulling apart, although, if desired, additional nails may be placed through the flap portions. Finally, a ridge roll of the type shown at 11 90 is placed in position to give a finished appearance.

95 From the foregoing description, it will be apparent that I have provided a type of structure wherein a very rigid roof is made and one wherein also all jointed connections are made water tight.

The ridge roll itself is preferably formed from sheet metal, and is so shaped as to adapt itself to the configuration of a ridge pole and the co-operating upper portions of 100 the roof sections. In this instance, said ridge roll comprises a substantially flat upper portion 12, which is adapted to be positioned upon the corresponding upper surface of the ridge pole 1, fastening elements 110 13 being employed to secure the same in a rigid position. The portion 12 terminates

in obliquely and downwardly directed sides 14, which extend substantially parallel with the roof sections 4. The lower edges of the sides 14 terminate in right angularly disposed supplemental sides 15, which are situated at right angles to said roof sections, the lower edges of the supplemental sides being formed so as to flushly engage with the undulating cross sectional formation of 10 the roof sections. By virtue of this ridge roll construction and the co-operation which exists between the same and the roof sections, a structure is provided which is convenient to assemble and erect and one where- 15 in the exclusion of weather, water or moisture is effectively provided for.

What I claim, is:

1. In a roof, the combination with a ridge pole, of a plurality of transversely curved and inclined roof sections cooperative with said pole, and suitably supported in connection therewith, a ridge roll positioned upon said pole and arranged to cover the joints defined between the meeting faces of 25 said sections and pole, said ridge roll being formed to include a flat upper portion arranged to directly contact with the upper portion of said pole, fastening devices arranged to pass through the flat upper portion 30 of said ridge roll and to directly connect the latter with said pole, said roll being further formed to include sides disposed parallel with said sections and in spaced relationship therefrom, and integral supplemental sides disposed at right angles to the first mentioned sides, said supplemental sides having their lower edges undercut to 35 evenly engage with the undulating curvature of said sections.
- 40 2. In a roof structure, the combination with a ridge pole, of a plurality of concave metallic roof sections, cooperatively supported in connection with said pole and sloping downwardly therefrom, a ridge roll

formed to include a substantially flat upper 45 portion, reversely inclined sides extending downwardly from the flat upper portion of said roll and in parallelism with said roof sections, supplemental sides disposed at the lower edges of said first named sides and in 50 angular relation with respect thereto, the said supplemental sides having the lower edges thereof formed to evenly engage with the concave surfaces of said sections, the said sides serving to cover the connections 55 between the said roof sections and said pole, and fastening devices arranged to pass through the flat upper portion of said roll, and to connect the latter with the upper portion of said pole.

3. In a roof structure, the combination with a ridge pole, of a plurality of transversely concave metallic roof sections having the upper edges thereof secured to the opposite sides of said pole, a metallic ridge 65 roll disposed upon the upper surface of said pole and arranged to cover the meeting joints defined by the connection between said sections and said pole, the said ridge roll being formed to include reversely and downwardly inclined sides extended away from said pole and in substantially parallel relationship with said roof sections, supplemental sides disposed at the lower edges of 70 said first named sides and in angular relation with respect thereto, the supplemental sides having their lower edges formed to 75 conform with the transverse configuration of said sections, and fastening devices situated between said sides for connecting the 80 roll to the upper part of said pole.

In testimony whereof I affix my signature in presence of two witnesses.

CHARLEY BURNETT.
